UNITED STATES PATENT OFFICE

FREDERICK E. GREENE, OF NEW HAVEN, CONNECTICUT, ASSIGNOR TO THE GREIST MANUFACTURING COMPANY, OF NEW HAVEN, CONNECTICUT, A CORPORATION OF CONNECTICUT

DESIGN FOR AN ASH TRAY

Application filed November 14, 1932. Serial No. 45,961. Term of patent 7 years.

To all whom it may concern:

Be it known that I, FREDERICK E. GREENE, a citizen of the United States, and a resident of New Haven, in the county of New Haven and State of Connecticut, have invented a new, original, and ornamental Design for an Ash Tray, of which the following is a specification, reference being had to the accompanying drawing, forming part thereof,

in which the figure is a perspective view of the ash tray.

I claim:

The ornamental design for an ash tray substantially as shown.

New Haven, Connecticut, November 10, 1932.

FREDERICK E. GREENE.
